CLAIM

The ornamental design for a cosmetic box, as shown and described.

DESCRIPTION

FIG. 1 is a top plan view of a cosmetic box, in an open position, showing my new design;

FIG. 2 is a top perspective view thereof;

FIG. 3 is a top plan view shown in an alternate position;

FIG. 4 is a top plan view in a closed position;

FIG. 5 is a bottom plan view thereof;

FIG. 6 is a front elevational view thereof, the side opposite being a mirror image of the side shown; and

FIG. 7 is a side elevational view thereof, the side opposite being a mirror image of the side shown.

FIG. 1

FIG. 2

FIG. 3

FIG. 5

FIG. 4

FIG. 6

FIG. 7
